United States Patent Office

Des. 207,399
Patented Apr. 11, 1967

207,399

AMBULANCE

Jeffrey Elgin, 1124 Fuller St. 45202; Gerald M. Halpin,
5310 Robert Ave. 45211; and Thomas Rotroff, 224
Southern Ave. 45219, all of Cincinnati, Ohio

Filed Aug. 24, 1966, Ser. No. 3,566

Term of patent 14 years

(Cl. D14—17)

Fig. 1

Fig. 2

Fig. 3

Fig. 4

FIG. 5

FIG. 6

FIG. 7

FIG. 1 is a side elevational view of an ambulance, showing our new design.

FIG. 2 is a top plan view of the same.

FIG. 3 is a rear elevational view of the same.

FIG. 4 is a front elevational view of the same.

FIG. 5 is a side elevational view thereof, in opened condition.

FIG. 6 is a rear elevational view; and

FIG. 7 is a front elevational view.

The side not shown is the same as the side shown.

We claim:

The ornamental design for an ambulance, as shown and described.
